PLANT FOR MIXING THE COMPONENTS OF CONCRETE AND THE LIKE

Filed April 3, 1929

Inventor:

Paul Grünberger

UNITED STATES PATENT OFFICE

PAUL GRÜNBERGER, OF JERUSALEM, PALESTINE

PLANT FOR MIXING THE COMPONENTS OF CONCRETE AND THE LIKE

Application filed April 3, 1929, Serial No. 352,249, and in Germany March 8, 1928.

If large amounts of concrete are to be produced, the several materials forming the components of the mixture are conveyed from the respective storing receptacles, for instance 5 silos, to the mixer by means of suitable conveying devices generally separately in such amounts as are required for one normal charge of the mixer, these amounts of the various materials being then thrown separately 10 into the charging hopper of the mixer and the conveying device returning thereafter from the mixer to the storing receptacle in order to fetch another amount of every material.

15 This tedious procedure is improved, according to the present invention, in this way that it is rendered possible to carry out at a time a plurality of different procedures, as regards the conveyance of the several materials in certain definite amounts whereby 20 much time is saved and the working costs are considerably reduced, I attain these objects by subdividing the conveying means, preferably also the charging hopper of the mixer, 25 into as many chambers or compartments as there are different materials required for the production of the concrete, and the sizes of said chambers or compartments are determined with consideration to the bulk of the 30 several amounts, that is to say, with consideration to the ratio of the various materials in the finished concrete. Furthermore, the storing receptacles, for instance the silos, are provided with discharging devices so arranged 35 as to allow of filling the said compartments in a certain proper order, as is all fully described hereinafter.

The invention is illustrated diagrammatically and by way of example on the accompanying drawing on which Figure 1 is a plan of a plant designed according to this invention; Figure 2 is a similar representation showing another constructional form, Figure 3 is a view of a mixer, a charging hopper for it, and a tipping truck, and Figure 4 is a plan of the members shown in Fig. 3, all as fully described hereinafter.

Referring to Fig. 1, A, B, and C denote 50 three silos or, more precisely, the lower ends thereof. The silos may be arranged side by

side, like B and C, or they may be spaced, like A and B. e denotes a truck running preferably on a track, as shown. In Fig. 1 the truck e is placed just in front of the silo A.

In the example shown it is assumed that 55 three working procedures are to be carried out at a time, and the truck is, therefore, subdivided into three main parts 1, 2 and 3, each of which is subdivided into three compartments 60 A', B' and C'. The size of these compartments, their capacity, corresponds to the proportion in which the three materials, viz, sand, gravel, and cement, are to be mixed with each other in order to form concrete. The sand is contained in the silo A, the gravel in the silo B, and the cement in the silo C. The compartments A' receive, thus, the sand from the silo A, the compartments B' receive the gravel from the silo B, and the compartments 65 C' receive the cement from the silo C. The partition walls f and f' (Fig. 1) between the three main parts of the truck extend preferably over the upper horizontal plane of the truck.

In the constructional form of the silos, as 70 shown in Fig. 1, each thereof is also subdivided into three main parts, of which each is subdivided into three chambers a, b and c, corresponding to the subdivision of the truck. I wish to indicate thereby that every silo 75 can, if desired, be used either for sand or for gravel or for cement.

Corresponding to the provision of three compartments for sand in the truck e, three discharge members d are provided at the 80 silo A, and for the same reason three discharge members d' for gravel are provided at the silo B, as well as three discharge members d'' for cement at the silo C. The position 85 of the discharge members at the silos is different, corresponding to the different places of the compartments A', B' and C' on the truck. Therefore when the truck is moved from the left to the right, first the three compartments A' are filled with sand; then the three compartments B' are filled with gravel; finally the three compartments C' are filled 90 with cement it being understood that the capacity of the several compartments corresponds to the proper proportions of the ma- 95 100

terials in the mixture from which the concrete is made.

In the modification shown in Fig. 2 the truck has only two main parts and these are so subdivided into compartments that the two compartments A' lie side by side so that it is possible to fill them at a time through one discharging member d^3 . a, b and c , as well as a^1, b^1 and c^1 denote subdivisions of the silo A. Entering into details concerning these subdivisions is, I think superfluous in view of the explanation already given with respect to the silo A of Fig. 1.

The truck is preferably a tipping truck, as shown in Fig. 3. The materials are thrown directly into the hopper g of the concrete mixer h . The hopper and the mixer receive the materials directly from the truck (or other conveying means) in the proper proportions, as already stated, so that not only much time is saved but also less hands are needed, in consequence whereof the manufacturing costs of the concrete are correspondingly reduced. The proper proportions of the materials are maintained practically automatically which is useful for the uniformity and the quality of the product.

The charging hopper g can be subdivided in conformity with the subdivision of the truck, as in Fig. 4, so that the several materials are separated from one another also in the hopper g and get mixed with each other only in the mixer h . There may be a common discharge slide for all compartments of the hopper, or there may be separate slides for the separate compartments, so that it is rendered possible to retain one or the other of the materials if, perhaps, a reason to do so should arise.

I wish it to be understood that I do not limit myself to the arrangements and combinations of parts shown in the drawing merely by way of example. The number of the silos, the eventual subdivision of the same, the subdivision of the trucks as regards the number of the main parts and the number of the compartments in every main part can be chosen according to the requirements of the given cases. The same is true of the conveyance of the materials from the truck or its equivalent to the mixer, viz, either directly, as in Fig. 3, or indirectly by suitable intermediate means, according to the site.

I claim:

1. A plant for carrying out at a time a plurality of different working procedures, especially mixing procedures for concrete mixers, comprising, in combination, a plurality of storing receptacles, the number of which corresponds to the number of the materials to be dealt with; a conveying member so arranged as to be adapted to be charged successively by said receptacles, and being subdivided in conformity with said number into main parts, each of which is subdivided

into compartments also in conformity with the number of the said receptacles, substantially as set forth.

2. A plant for carrying out at a time a plurality of different working procedures, especially mixing procedures for concrete mixers, comprising, in combination, a plurality of storing receptacles, the number of which corresponds to the number of the materials to be dealt with; and a truck running on a track extending along said receptacles, said truck being subdivided in conformity with said number into main parts, each of which is subdivided into compartments also in conformity with the number of said receptacles, substantially as set forth.

3. A plant for carrying out at a time a plurality of different working procedures, especially mixing procedures for concrete mixers, comprising, in combination, a plurality of storing receptacles, the number of which corresponds to the number of the materials to be dealt with; a tipping truck subdivided in conformity with said number into main parts, each of which is subdivided into compartments also in conformity with the number of the said receptacles; and a mixer charging hopper subdivided correspondingly so as to be adapted to co-operate with said truck, substantially as set forth.

In testimony whereof, I have signed my name to this specification at Jerusalem, Palestine, this 14th day of March, 1929.

PAUL GRÜNBERGER.
